FIG. 3

UNITED STATES PATENT OFFICE.

HARRY A. LEWIS, OF NORRISTOWN, PENNSYLVANIA, ASSIGNOR OF ONE-HALF TO
ALAN D. WOOD, OF PHILADELPHIA, PENNSYLVANIA.

MATERIAL-HANDLING APPARATUS.

Application filed October 17, 1924. Serial No. 744,199.

To all whom it may concern:

Be it known that I, HARRY A. LEWIS, a citizen of the United States, and a resident of Norristown, in the county of Montgomery and State of Pennsylvania, have invented a new and useful Improvement in Material-Handling Apparatus; and I do hereby declare the following to be a full, clear, and exact description thereof.

10 My invention relates to material handling apparatus and particularly to annealing furnaces and apparatus for handling the material to be annealed.

The invention constitutes an improvement 15 over my prior Patent 1,367,061, issued February 1, 1921.

One object of my invention is to provide an improved form and arrangement of furnaces of the character referred to.

20 Another object of my invention is to provide improved means for supporting and manipulating the material to be treated in the furnace.

One of the forms which my invention may 25 take is shown in the accompanying drawing wherein Fig. 1 is a view, partially in end elevation and partially in section, of a furnace arrangement and operating mechanism embodying my invention; Fig. 2 is a 30 view, partially in side elevation and partially in section, of the apparatus of Fig. 1; and Fig. 3 is a sectional plan view of the apparatus of Figs. 1 and 2.

The furnace comprises a lower compartment 35 4 hereinafter termed the water chamber, having a bottom wall 5, end walls 6 and side walls 7 that may be formed of reinforced concrete or other suitable material. Supported upon the side and end 40 walls of the chamber 4 is an annealing chamber 8 through which the articles to be heated are passed. The chamber is provided with the usual top and side walls and the end doors 9 and 10. The chamber 8 45 is supported intermediate its ends by longitudinally and transversely extending I-beams 11 and 12, (Fig. 2) whose ends are imbedded in or supported by the walls 6 and 7 of the lower chamber 4.

50 The bottom of the chamber 8 is preferably composed (Fig. 3) of sheet iron 13, red brick 14 and fire brick 15, though of

course other material may be employed if desired.

The bottom of the annealing chamber 8 55 is provided with elongated openings 16 that are disposed in staggered relation as shown in Fig. 3, for a purpose hereinafter to be described. The furnace is likewise provided with flues 17 that lead to the stack 60 18, and the stack 18 is provided with a damper 19. The chamber 8 may be heated either electrically or by combustion.

The water for the chamber 4 is supplied from any desired source, and the level 65 therein is preferably maintained at the level of the overflow pipe 20 (Fig. 1). A drain valve 20^a is also provided to clear the chamber of water when desired. The overflow and the water is drained off to a cooling 70 reservoir through a pipe 21. Water may of course be supplied to the chamber 4 continuously or intermittently, as desired.

Pairs of pillars or piers 22 are mounted 75 within the chamber 4 for supporting shafts 23 upon which are mounted rocker arms 24, pivotally connected to and spaced axially of the shafts 23. To the outer end of each arm 24 is connected a lever or oscillator 25. The oscillators 25 are provided intermediate 80 their ends with enlargements 26 that are ringlike or annular in form, for the reception of eccentrics 27. The eccentrics 27 are rigidly secured to shafts 28 that are rotatably supported in bearings 29 (Fig. 1) and 85 are provided on their outer ends with bevelled gear wheels 30, some of the gear wheels being omitted in Fig. 2 for the sake of clearness.

The gear wheels 30 are driven by bevel 90 pinions 31 that are mounted upon a shaft 32 which is connected through a bevel gear wheel 33 with a bevel pinion 34 mounted upon a shaft 35 which is driven by differential mechanism 36 having worm wheels 37 that are driven by motors 38. This arrangement of motors and differential mechanism makes for uniformity of speed and smoothness of movement of the apparatus just described.

To operate the apparatus, the doors 9 and 10 are first opened by means of a motor 40 which, through suitable connections, moves the chains 41 that are connected to

2: cords or cables 42, that pass around suitable sheaves, as shown in Fig. 2, and are connected to the doors 9 and 10 to raise the same. The motors 38 are then started 5 to operate the eccentrics 27 and impart an oscillatory movement to the levers 25. Sheets of material 43 are supplied through the furnace door 9 and are engaged by the upper ends of the levers 25. Preferably the levers 25 are actuated at a relatively fast speed during this stage of the operation. As soon as the material has entered the furnace the doors are closed and the speed of the motors 38 reduced so that 10 the material will move through the furnace at a low rate of speed in order that it may be properly heat-treated by the time it reaches the outlet door 10. The purpose in continuously moving the sheets of material 15 43 while in the furnace is to avoid streaking or marking of the sheets by reason of their contact with the levers 25, and to maintain the heated air in the furnace in a state of agitation so that sheets will be 20 uniformly heated.

The purpose of the water chamber is to lubricate the bearings of shafts 32, 23 and 28 that are located within the chamber as well as the bearings for the other moving parts 30 contained therein, and also to prevent such mechanism from becoming overheated through heat being conducted thereto through the annealing chamber. Further the water protects the bearings from dust 35 which may fall through the openings 16, in that such dust will not circulate through the chamber 4.

The shafting within the chamber 4 may 40 preferably run in rubber bearings without oil. A stuffing box 45 is provided in the end of the chamber 44 to prevent leakage of water along the shaft 32.

Claims to the general arrangement above described form the basis of my application, 45 Serial No. 743,986 filed October 16, 1924.

Various changes in detail and general arrangement may be made without departing from the spirit and scope of the invention as defined in the accompanying claims.

50 I claim as my invention:

1. Means for moving material comprising a plurality of levers mounted in staggered relation to the line of movement of the material and with their outer ends disposed in 55 position to engage and move said material, means for pivotally supporting said levers at their inner ends, and means for imparting outward and forward movement to the outer ends of said levers in an annular path which is parallel to the path of movement of the material.

2. Material handling apparatus comprising levers whose outer ends are offset vertically relatively to one another and adapted 65 to engage and move the material, and means

for imparting movement to the outer ends of said levers, through an annular path, to engage and move said material, the said levers being mounted adjacent to one another and movable synchronously to alternately 70 engage said material.

3. Material handling apparatus comprising levers whose outer ends are adapted to engage and move the material, and means for imparting an outward and forward 75 movement to the outer ends of said levers, comprising eccentrics connected to said levers intermediate their ends, the inner ends of said levers being pivotally supported against substantial movement forwardly. 80

4. Material handling apparatus comprising levers whose outer ends are adapted to engage and move the material, and means for imparting an outward and forward movement to the outer ends of said levers, comprising eccentrics connected to said levers intermediate their ends, the inner ends of said levers being pivotally connected to the ends of rocker arms that extend in a direction substantially at right angles to the 85 levers, and which are in turn pivotally connected to a fixed support to prevent substantial forward movement of said inner ends.

5. Material handling apparatus comprising 90 a pair of levers whose outer ends are adapted to engage the material to be moved, rocker arms to which the inner ends of the levers are connected, and means for imparting an eccentric movement to one of said levers intermediate its ends in one direction and to simultaneously impart a similar movement to the other lever in the opposite direction, whereby said levers are caused to alternately move toward and from the material and in a direction parallel to the path of movement of said material. 95

6. Material handling apparatus comprising 100 a plurality of pairs of levers whose outer ends are adapted to engage the material to be moved, rocker arms to which the inner ends of the levers are pivotally connected, and means for imparting an eccentric movement to one of said levers intermediate its 105 ends in one direction and to simultaneously impart a similar movement to the other lever in the opposite direction, whereby said levers are caused to alternately move against and away from the material and in a direction substantially parallel to the path of movement of said material while in engagement therewith, and a common driving mechanism for said pairs of levers. 110

7. Material handling apparatus comprising 115 a plurality of pairs of levers whose outer ends are adapted to engage the material to be moved, rocker arms to which the inner ends of the levers are connected, means for imparting an eccentric movement to one of 120 said levers intermediate its ends in one di- 125

rection and to simultaneously impart a similar movement to the other lever in the opposite direction whereby said levers are caused to alternately move toward and from the material and in a direction parallel to the path of movement of said material to move the same, and a common driving mechanism for

said pairs of levers, the pairs of levers being disposed parallel to the path of movement of the material. 10

In testimony whereof I the said HARRY A. LEWIS have hereunto set my hand.

HARRY A. LEWIS.
